WITNESS

UNITED STATES PATENT OFFICE.

JOHN D. MAIER, OF CHARLESTOWN, MARYLAND.

TOBACCO PIPE.

Application filed May 20, 1921. Serial No. 471,051.

To all whom it may concern:

Be it known that I, JOHN D. MAIER, a citizen of the United States, residing at Charlestown, in the county of Cecil and 5 State of Maryland, have invented new and useful Improvements in Tobacco Pipes, of which the following is a specification.

The object of my present invention is the provision of a tobacco pipe constructed with 10 a view to affording a cool smoke and to be expeditiously and thoroughly cleaned when occasion demands without the assistance of extraneous means other than a wad of soft paper or other appropriate soft material.

15 To the attainment of the foregoing, the invention consists in the improvement as hereinafter described and definitely claimed.

In the accompanying drawings, forming part of this specification:—

20 Figure 1 is a longitudinal vertical central section illustrative of my novel tobacco pipe.

Figure 2 is a view partly in elevation and partly in section showing the ferrule and the tube associated therewith.

25 Figure 3 is an enlarged transverse section taken in the plane indicated by the line 3—3 of Figure 1.

Figure 4 is a side elevation of the removable element of the improvement.

30 Similar numerals of reference designate corresponding parts in all of the views of the drawings.

In accordance with my invention the pipe bowl 1 and its stem 2 are formed in one 35 piece, and in the stem 2 is provided a bore 3 of large diameter throughout its length and extending from the bottom portion of the bowl rearwardly as illustrated. Permanently arranged on the rear reduced portion 40 4 of the stem 2 is a metallic ferrule 5, and appropriately fixed in the said ferrule 5 is the rear comparatively large portion 6 of a metallic tube 7 which is designed to tightly fit in the stem bore 3 and to remain permanently therein. For the sake of lightness the 45 ferrule 5 and the tube 7 are preferably of aluminum. Snugly fitting in the portion 6 of the tube 7 is the reduced forward portion of a removable mouth piece 8 which may be 50 of any material compatible with the purpose of my invention, and arranged removably in the tube 7 is the smoke cooling and cleaning element of the improvement; the said element being numbered 9 and being provided with a stem 10 in which is a longitudinal groove 11 for the passage of smoke.

The stem 10 is tightly fitted in the mouth piece 8 so that when the said mouth piece 8 is removed the element 9 will also be removed. In addition to the stem 10 the element 9 includes a shank 12 integral with and extending forwardly from the enlargement 13 at the forward end of the stem 10, and a spiral fin 14 which is designed to snugly fit in the tube 7 and form a tortuous smoke 60 passage with a view to cooling the smoke before it reaches the mouth of the smoker. At its forward end the shank 12 is provided with a hook 15 which hook extends about the proportional distance illustrated 65 forwardly of the forward end of the fin 14 for a purpose hereinafter set forth. For the sake of lightness the element 9 is also preferably formed of aluminum, but it will be understood from the foregoing that the material or materials of which the ferrule 5, tube 7 and removable element 9 are formed are not of the essence of my invention. When the novel pipe is to be used the parts are arranged as illustrated in Figure 1, and 70 consequently it will be understood that in passing through the tube 7 the smoke will be caused by the spiral fin 14 to follow a tortuous course en route to the smoker's mouth so that when the smoke reaches the 75 mouth it will have been materially cooled. 80

Incident to the use of the pipe nicotine and other sediment will settle at the bottom of the tube 7 so that when the mouth piece 8 and the element 9 are withdrawn rectilinearly, the spiral fins 14 will operate to scrape and remove the collected nicotine and other sediment out of the tube 7. Then when a wad or swab of soft paper or other appropriate soft material is placed on the 85 hook 15, and the element 9 is reinserted in the tube 7 the said wad or swab will be forced forwardly through the tube 7 so as to thoroughly clean and dry the same. The 90 said wad or swab is left in the bottom of the bowl 1, and the element 9 is again withdrawn rearwardly with the mouth piece 8 whereupon the hook end of the element 9 is introduced through the mouth of the bowl 1 and the hook end 15 is utilized as a pick 95 to engage the wad or swab and withdraw the same from the bowl. Manifestly in this 100 way the pipe may be expeditiously and thoroughly cleaned, and then when the element 9 and the mouth piece 8 are properly positioned relatively to the tube 7 from the rear, the pipe will be restored to condition for use. 105

It will also be manifest from the foregoing that so far as outward appearance is concerned my novel pipe presents the usual neat appearance of an ordinary pipe.

5 It will further be appreciated from the foregoing that my improvement is simple and inexpensive in construction and is adapted to materially prolong the usefulness of the pipe as a whole.

10 Having described my invention, what I claim and desire to secure by Letters Patent, is:—

In a tobacco pipe a bowl and a stem extending from the bowl and having a bore in

communication with the interior of the bowl 15 and also having an exteriorly reduced rear end, a ferrule permanently fixed on said reduced end of the stem, a tube having a rear enlarged portion permanently secured in the ferrule, said tube resting snugly in the stem 20 of the pipe and being open at its ends, a mouth piece removably arranged in the rear enlarged portion of the tube, and cleaning means removably arranged in the tube and removable from the pipe with the mouth 25 piece.

In testimony whereof I affix my signature.

JOHN D. MAIER.
